CLAIM

The ornamental design for a set of handles for a mirrored tray, as shown and described.

DESCRIPTION

FIG. 1 is a top view of the tray in accordance with the invention;

FIG. 2 is a side elevational view thereof, the side opposite being a mirror image of the side shown;

FIG. 3 is an end elevational view thereof, the side opposite being a mirror image of the side shown; and

FIG. 4 is a bottom plan view thereof.
